HOLLOW UNIFORM-TYPE BUTTON

Henry A. Smitt, Panama, C. Z.

Application February 3, 1941, Serial No. 377,264

3 Claims. (Cl. 24—104)

My invention relates to certain new and useful improvements in buttons of the detachable kind, and particularly to the type used on uniforms.

It particularly has for its object, to provide a button which can be used on garments having no holes, such as are provided for the button shanks of one-piece detachable buttons, and to that end the invention provides a hollow button having two pin-receiving holes in its back, and a fastener composed of a head and two pin shanks which, when stuck through a garment, can be projected through the holes in the back of the button and anchored to the button.

Other objects will in part be obvious and in part be pointed out hereinafter.

To the attainment of the aforesaid objects and ends the invention still further resides in the novel details of construction, combination and arrangement of parts, all of which will be first fully described in the following detailed description and then be particularly pointed out in the appended claims, reference being had to the accompanying drawing, in which—

Fig. 1 is a side elevation and part vertical section showing my invention in use, the garment through which the dual shank projects being shown in dot and dash lines.

Fig. 2 is an elevation (parts being broken away) viewed 90° from Fig. 1.

Fig. 3 is a rear elevation of my invention.

Fig. 4 is a perspective view of the attaching head with the dual shank in the position it assumes when anchored (Figs. 1 and 2).

Fig. 5 is a view similar to Fig. 4, with the shanks in the release position.

In the drawing, in which like numerals of reference indicate like parts in all the figures, 1 is the hollow button whose back adjacent the center is pierced with two holes 10 to receive the shanks 3 and 5 of the fastening unit.

The fastening unit comprises a head 2 from one face of which there projects a pin-shank 3 whose pointed end 4 is bent laterally at right angles. The shank 3 is secured in the head 2 against movement. The head 2 also has a hole 11 through which the pin-shank 5 passes. The pointed end 6 of this shank 5 is also bent over at right angles. The shank 5, after passing through the hole 11, is looped at 7, over the head 2, the end 8 of the loop lying in a groove 9 in the face of the head 2 which lies adjacent the garment 12. The shank 5 is rotatable in the head 2, but is not movable substantially in a longitudinal direc-

tion in the head, being held against such movement by the loop 7.

The shank 3 may be made of stiff, rigid material, but the shank 5 should be made of a stiff material having, however, a certain amount of spring so as to enable the loop end 8 to ride into and out of the groove 9 upon rotating the shank 5.

In order to apply the button to a garment, the points 4 and 6 of the pin-shanks 3 and 5, respectively, are positioned as in Fig. 5. The points are then passed through the garment and the button 1 is slipped onto the points 4 and 6 and beyond the bends onto the shanks proper 3 and 5. The loop 7 is then turned from the position of Fig. 5 to that of Figs. 1, 2, 3 and 4, to cause the points 4 and 6 to extend in opposite directions and thus anchor the button to the shank.

From the foregoing description, taken in connection with the accompanying drawing, it is thought that the construction, use and advantages of the invention will be clear to those skilled in the art.

What I claim is:

1. A hollow button having a back provided with two pin-receiving holes, a head, two shanks mounted in the head and projecting from one face of the same, each shank having its projected end bent over at approximately right angles, said bent-over ends being pointed for piercing a garment and entering the pin-receiving holes of the button, one of said shanks being rigidly mounted on the head and the other shank being rotatable in the head on its own axis, said rotatable shank and said head having cooperative latching elements for holding said rotatable shank in either of two positions.

2. A hollow button having a back provided with two pin-receiving holes, a head, two shanks mounted in the head and projecting from one face of the same, each shank having its projected end bent over at approximately right angles, said bent-over ends being constructed to pierce a garment and enter the pin-receiving holes of the button, and means by which said bent-over ends may be located to point in the same direction or in opposite directions at will, said means comprising the mounting of one shank in the head rigidly and the mounting of the other shank in the head rotatably, said rotatable shank and said head having cooperating latching elements to hold the shank in position to secure or release the button as desired.

3. A hollow button having a back provided with

two pin-receiving holes, a head, two shanks mounted in the head and projecting from one face of the same, each shank having its projected end bent over at approximately right angles, said bent-over ends being constructed to pierce a garment and enter the pin-receiving holes of the button, and means by which said bent-over ends may be located to point in the same direction or in opposite directions at will, said means comprising the mounting of one shank in the head 10

rigidly and the mounting of the other shank in the head rotatably, and providing the rotatable shank and head with latching elements to hold the shank in position to secure or release the button as desired, said latching elements comprising a groove in the head and a head-embracing resilient loop on the rotatable shank for cooperation with said groove.

HENRY A. SMITT.
